ERNEST H. BENNETT, OF EAST ORANGE, NEW JERSEY, ASSIGNOR TO JOHN H. BROMLEY AND EDWARD BROMLEY, OF PHILADELPHIA, PENNSYLVANIA, COPARTNERS TRADING AS JOHN BROMLEY & SONS.

DESIGN FOR A RUG.

SPECIFICATION forming part of Design No. 34,913, dated August 6, 1901.

Application filed July 6, 1901. Serial No. 67,365. Term of patent 8½ years.

To all whom it may concern:

Be it known that I, ERNEST H. BENNETT, a citizen of the United States, residing at East Orange, New Jersey, have invented and produced a certain new and original Design for Rugs, of which the following is a full, clear, and exact description, reference being had to the accompanying drawings, forming a part of this specification.

10 My design is applicable to and intended for the surface ornamentation of a woven rug.

In its essentials it consists, as shown in the drawings, of a border a, of connected flowers and leaves, inclosing a field center surrounded 15 by lines b c, curved inwardly at their connecting ends, and within the same a series of small leaf figures d, filling the central space.

I claim—

20 The design for a rug, substantially as shown and described.

In testimony whereof I have hereunto affixed my signature this 27th day of May, A. D. 1901.

ERNEST H. BENNETT.
